Primary Examiner — Brandon M Rosati*Assistant Examiner* — Marissa J Cash(74) *Attorney, Agent, or Firm* — Dunstan H. Barnes; McAndrews, Held & Malloy, Ltd.; Eugene H. Nahm(57) **CLAIM**

The ornamental design for an aircraft, as shown and described.

DESCRIPTION

FIG. 1 is a front perspective view of an aircraft showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom perspective view thereof.

The broken lines in the drawings illustrate portions of the aircraft that form no part of the claimed design.
